UNITED STATES PATENT OFFICE.

ABRAHAM ROBINSON, OF NEW YORK, N. Y.

STRAP-CLAMP.

1,188,206.

Specification of Letters Patent. Patented June 20, 1916.

Application filed September 25, 1915. Serial No. 52,559.

To all whom it may concern:

Be it known that I, ABRAHAM ROBINSON, a citizen of the United States, and a resident of New York, in the county of New York and State of New York, have invented certain new and useful Improvements in Strap-Clamps, of which the following is a specification.

My invention relates to means for holding straps in place upon a desired support, such as the straps supporting the springs in the upholstering of furniture, and one of the main objects thereof is to provide such means which are positive in action as well as permanent and which will not injure the fabric of the straps nor permit said straps to have strain placed thereon other than across the entire width thereof, thus insuring full efficiency of the straps.

My invention is fully described in the following specification, of which the accompanying drawings form a part, in which like characters refer to like parts in each of the views, and in which:

Figure 1 is a sectional view of a portion of the frame of a chair provided with an upholstered seat provided with my invention; Fig. 2 is an enlarged, detached, outer plan view of my invention; Fig. 3 is a section taken on the line 2—2 of Fig. 2; and Fig. 4 is a perspective view of the inner surface of my invention, as separated from the strap.

In Figs. 1 and 2 I have illustrated, fragmentarily, and in section, the frame 5 of a chair provided with the bottom frame formed by strips 6, shown as removable from the frame 5, and to which the conventional strips or straps 7 are secured to sustain the springs 8 in turn supporting the seat cushion 9. My invention is designed to hold the ends of said straps to supplant the tacks now employed and which tacks frequently pull out or cause the fabric of the straps to tear and thus render the straps functionally useless or practically so. My clamps, however, insure positive and permanent anchoring of the ends of the straps, although said clamps are removable if removal is desired for any purpose and, further, an even strain across the entire width of the straps is insured instead of at the points of present tack attachment.

My invention consists of a plate 10 pro-

vided with a longitudinal slot 11 and with a plurality of screw-holes 12 for the passage of screws 13 to hold the same to the frame strips 6; the outer surface of the plate 10 is smooth but the inner surface is provided with three rows of teeth, 14, 15, and 16, of which the first two rows border the slot 11 and the last row borders the edge farthest removed from the slot 11. These rows of teeth are clearly shown in Fig. 4, and it will be particularly noted that the teeth of the rows 14 and 15 are staggered with respect to each for a reason later pointed out.

In practice, one end of a strap 7 is passed through the slot 11, from the smooth side of the plate 10, and laid over the rows 15 and 16 of teeth, after which the body of the strap is passed around the square smooth edge 17 of the plate and laid over all of the rows of teeth and, when the strap is in this position, the plate 10 is screwed in place, the teeth of the several rows piercing the material of the strap 7 and entering the wood into which the screws 13 are driven, this being clearly illustrated in Fig. 3. The body of the strap 7 is drawn taut over the inner surface of the plate 10 previous to securing the latter in position in order that the strain placed upon the strap by the weight of a person will be carried entirely by the smooth edge 17 of the plate, although the row 14 of teeth may contribute somewhat to the anchoring of the strap 7, and the rows 15 and 16 may also contribute thereto, but the principal function of the rows 15 and 16 is to hold the end of the strap 7 against any possibility of slipping. Inasmuch as these straps are usually made of coarse fabric which is pierced by the teeth, I stagger the teeth of the rows 14 and 15 in order to prevent the teeth of one row from enlarging a possible tear by a tooth of the other row, in other words, I double the holding power of the teeth in the two rows by arranging them between different longitudinal threads of the fabric.

If the screws 13 should become loosened from any cause, the teeth of the several rows would not hold the strap in all probability, but the edge 17 will and does sustain any weight that might be placed upon the strap, the downward pressure of the body of the strap on the end of the strap maintaining

said end in positive engagement with the teeth of the row 16, and this prevents slipping of the strap with respect to the plate 10. This prevention against slipping of the strap is also aided by the screws 13, and it will thus be seen that a positive anchoring of the strap at its ends results with the strain evenly distributed across the entire width of the strap. The clamp may be formed of a stamping from sheet metal, as the rows 14 and 15 of teeth may be formed of the material struck up to form the slot 11 and the row 16 may be formed of a flange struck up on the corresponding edge of the plate 10, but this is not essential, as I may elect to cast the clamp, drop-forged the same, or produce it in any other desired or commercial manner.

As will be understood, I do not limit myself to the use of my invention illustrated and hereinbefore described, as many other uses thereof will suggest themselves, and I reserve the right to make such structural changes over the form shown and described as come within the scope of the appended claims and within the spirit of the invention.

Having fully described my invention,

what I claim as new, and desire to secure by Letters Patent, is:—

1. As an article of manufacture, for use with a strap, a clamp, comprising a slotted plate provided with a row of teeth along one edge thereof and with a row of teeth along each edge of said slot.

2. As an article of manufacture, for use with a strap, a clamp, comprising a slotted plate provided with a row of teeth along one edge thereof and with a row of teeth along each edge of said slot, the teeth of said last named rows being staggered with respect to each other.

3. As an article of manufacture, for use with a strap, a clamp, comprising a slotted plate provided with a row of teeth along one edge thereof, with a smooth edge at the opposite edge thereof, and with a row of teeth along each edge of said slot.

In testimony whereof I have signed my name to this specification in the presence of two subscribing witnesses.

ABRAHAM ROBINSON.
